Fig. 2

Fig. 1

Fig. 3

Figure 1 is a front view of a refrigerator cabinet showing my new design;

Figure 2, is a top plan view thereof; and
Figure 3 is a side elevational view thereof.

The dominant feature of my design resides in the portions shown in full lines. The side not shown is substantially the same as the side shown and the rear is substantially plain.

I claim:

The ornamental design for a refrigerator cabinet, as shown and described.
